MICROFILM VIEWER

Warren C. Portman, Peekskill, and Alex J. Weinstein,
Croton-on-Hudson, N.Y., assignors to The Ednalite
Corporation, Peekskill, N.Y., a corporation of New
York

Filed Oct. 11, 1968, Ser. No. 13,995

Term of patent 14 years

Int. Cl. D16—02

U.S. Cl. D61—1

FIG. 1 is a perspective view showing the design of a microfilm viewer according to this invention;

FIG. 2 is a side elevational view;

FIG. 3 is a back elevational view; and

FIG. 4 is a top plan view of the upper cabinet portion only; the lower base portion having been omitted for convenience of illustration.

We claim:

The ornamental design for a microfilm viewer, substantially as shown and described.
